CLAIM

The ornamental design for a laser engraver, as shown and described.

DESCRIPTION

FIG. 1 is a front perspective view of a laser engraver design showing my new design.

FIG. 2 is a front view of a laser engraver.

FIG. 3 is a rear view of a laser engraver.

FIG. 4 is a left side view of a laser engraver.

FIG. 5 is a right side view of a laser engraver.

FIG. 6 is a top view of a laser engraver.

FIG. 7 is a bottom view of a laser engraver.

FIG. 8 is a rear perspective view of a laser engraver.

FIG. 9 is an enlarged view of a laser engraver taken from portion 9 shown in FIG. 1.

FIG. 10 is an enlarged view of a laser engraver taken from portion 10 shown in FIG. 1.

FIG. 11 is an enlarged view of a laser engraver taken from portion 11 shown in FIG. 1; and,

FIG. 12 is an enlarged view of a laser engraver taken from portion 12 shown in FIG. 8.

The small uniform dash broken lines depict portions of the laser engraver that form no part of the claimed design.

The large uniform dash broken lines represent boundaries of the enlarged portions and form no part of the claimed design.

1 Claim, 12 Drawing Sheets
